ORGAN

Floyd A. Firestone, Ann Arbor, Mich.
Application June 19, 1929, Serial No. 372,200

19 Claims. (Cl. 84—1)

The invention relates to an improvement in organs wherein the sound is produced by the generation of alternating currents of the proper frequency which currents are amplified and applied to a loud speaker. The objects of the improvements are to obtain an organ of greater tonal possibilities, more compact, and less expensive than the present compressed air organ.

The compressed air organ as usually built uses a separate set of pipes for each tone quality; thus, there is a full scale of pipes for imitating the clarinet tone, another for the trumpet, another for the flute, etc. A complete organ consists of about six thousand pipes together with the necessary equipment for supplying compressed air at different pressures. This equipment occupies a very large amount of space and costs \$50,000 or more. Furthermore, its variety of tone qualities is limited by the inventiveness of the designers in producing pipes; many orchestral instruments have never been successfully imitated by the organ. My organ consists of one set of equipment which can by suitable manipulation imitate the tone of any musical instrument; it is less expensive to construct than the compressed air organ and requires only as much space as a grand piano.

A musical tone consists of a fundamental tone and a number of harmonics. The pitch of the musical tone is determined by the number of vibrations per second, commonly called the frequency, constituting the fundamental tone. The harmonics have frequencies which are integral multiples of the fundamental frequency. Thus, if the fundamental frequency is 200 cycles per second, the second harmonic frequency will be 400, the third harmonic frequency 600, etc. The quality of a musical sound is that characteristic which enables us to distinguish the sound of the clarinet from that of the violin, or the piano from the banjo. The quality is determined by the intensity of the harmonics relative to the fundamental; by the rate at which the intensity of the fundamental and harmonics grows and decays at the beginning and end of a note, commonly called the attack; and by the accompanying noises such as the hiss of the violin bow or the clarinetist's breath. My invention provides means by which the above three factors which determine the tone quality may be controlled at will by the performer. It is at present held by many authorities that the phase of the harmonics relative to the fundamental and to each other does not affect the tone quality but if the reverse should be found to be true it is also pos-

sible for me to control the relative phases of the various component tones.

My device contains a separate alternating current generator for each fundamental and each harmonic of all the notes of the organ. These generators are controlled by the keys on the keyboard of the console. (The console is that part of an organ which comprises the keyboards of the various manuals; the pedal keyboard, if any; and the necessary controls, if any, for regulating the loudness and tone quality of the notes produced). The currents are then amplified if necessary with a vacuum tube amplifier whose amplification is continuously variable for controlling the loudness; the amplified currents are applied to a loud speaker capable of converting electrical energy into acoustical energy.

Let us now consider what frequencies of alternating current must be produced in order to sound all of the C's on the organ including their harmonics. There are on the organ 9 C's having the following frequencies in cycles per second: 16, 32, 64, 128, 256, 512, 1024, 2048, and 4096. The lowest of these would have a fundamental and harmonics of the following frequencies: 16, 32, 48, 64, 80, 96, 112, 128, 144, etc. Some of these harmonic frequencies are the same as the fundamental frequencies of the other C's while some are different. The note having a 32 cycle fundamental has frequencies of 32, 64, 96, 128, 160, etc. Some of these harmonic frequencies are the same as those in the previous list for the 16 cycle fundamental. Thus, when one considers the 9 C's and, say, 20 harmonics of each, leaving out those harmonics having frequencies higher than 4096 cycles he finds that about 60 different frequencies are required. For the C sharps, 60 more different frequencies must be produced. Since there are twelve notes in one octave the production of all the notes in the scale with their first twenty harmonics, leaving out the harmonics above 10,000 cycles, would require 720 frequencies. It is obvious that if the device is to be commercially practicable each generator must be extremely simple.

Figs. 1a and 1b illustrate the principle of a single alternating current generator, which principle may be used in applying my invention. Figs. 2a, 2b, and 2c show a practical combination of a large number of alternating current generators utilizing the above principle. Fig. 3 shows the method of driving a number of similar groups of generators to produce all the frequencies needed in producing the notes of the musical scale. Fig. 110

REISSUED

4 gives the wiring diagram of a typical portion of the complete organ.

For purposes of sound production no distinction need be made between alternating current and direct current with alternating current superposed. A simple alternating current generator capable of producing sufficient voltage to actuate the grid circuit of a vacuum tube can be produced in many different ways, but the method which I prefer is shown in principle in Fig. 1. A rotating metallic disc 1 on a shaft 2 is mounted in bearings 3 and 4 and driven by the synchronous motor 5 through the pulleys 6 and 7 and belt 8. Around the disc is a row of equally spaced holes 9. Two strips of metal 10 and 11 called inductors are mounted on insulating blocks 12 and 13 in such a manner that the holes 9 run close to them. If the switch 14 is closed on point 15 the battery 16 will charge the inductor 10. Owing to the electrostatic capacity between inductor 10 and inductor 11 through the holes 9 the potential of the inductor 11 will always be greater when it is opposite a hole 9 than when it is opposite the grounded metallic disc 1 between the holes 9. Thus an alternating potential will be developed on the inductor 11 having the frequency with which holes 9 pass the inductor 11. By properly shaping the inductor 11 and adjusting its distance from the holes 9 a pure wave free from harmonics can be obtained. The voltage thus generated may be taken to the conventional vacuum tube amplifier 17 which is connected to the loud speaker 18 through the potentiometer 19. The rate at which the generator builds up its voltage when the switch 14 is closed is governed by the resistance 21 and the condenser 22. The inductor 10 does not arrive at the full voltage of the battery until the battery has charged the condenser 22 through the resistance 21. It is well known that the time in seconds required to charge a condenser through a resistance is roughly equal to the product of the capacity in farads and the resistance in ohms. Thus by adjusting the resistance 21 the generator may be made to build up its voltage instantly or gradually over a period of several seconds. To stop the generation of voltage it is necessary to discharge inductor 10. This is done through the resistances 23 and 21 by whose regulation the inductor 10 can be discharged instantly or gradually. Experiment has shown that if the inductor 10 is charged to 200 volts the inductor 11 will deliver about 0.05 volts alternating current to the amplifier 17, a value ample for the operation of an amplifier.

The final form of generator group shown in Fig. 2 is arrived at by the expansion of the principle of Fig. 1 by the use of three discs on one shaft, each disc having many rows of holes and each row of holes having one inductor on each side of and close to the disc. For simplicity each disc in Fig. 2 is drawn with only 6 rows of holes although in practice a larger number is required as explained fully further on in this paragraph. 24, 25, and 26 are the three metallic discs which are fixed to the shaft 27. Shaft 27 is mounted in the bearings 28 and 29 and is driven by belt 30. 31, 32, and 33 are the insulated primary inductor groups to which the direct polarizing voltage is applied, there being a separate insulated metallic inductor plug for each row of holes. 34, 35, and 36 are the corresponding insulated secondary inductor groups from which the alternating currents are derived, there being a separate insulated metallic inductor plug for each row of holes. Arranged in any convenient manner on discs 24,

25, and 26 are concentric circular rows of holes, there being one each of rows having the following numbers of holes: 1, 2, 3, 4, 5, 6, 7, 8, 9, 10, 11, 12, 13, 14, 15, 16, 17, 18, 19, 20, 22, 24, 26, 28, 30, 32, 34, 36, 38, 40, 44, 48, 52, 56, 60, 64, 68, 72, 76, 80, 88, 96, 104, 112, 120, 128, 136, 144, 152, 160, 176, 192, 208, 224, 240, 256, 272, 288, 304, and 320. The purpose of using three discs 24, 25, and 26 is merely to have sufficient room for so many rows of holes. The rows which generate the fundamental frequencies in the above group have the following numbers of holes: 1, 2, 4, 8, 16, 32, 64, 128, and 256. The rest of the rows are necessary for providing the 20 harmonics of each of these fundamentals, all rows having more than 320 holes having been omitted as being of too high a frequency.

If the generator group of Fig. 2 is driven at 16.00 revolutions per second it is capable of producing all the frequencies necessary for all the C's of the scale and all their necessary harmonics. An exactly similar generator group if driven at a speed of 16.95 revolutions per second is capable of producing all the frequencies necessary for all the C sharps of the scale and all their necessary harmonics. The frequencies of all the notes of the musical scale and all their necessary harmonics can be produced by 12 similar generator groups running at the following speeds in revolutions per second: 16.00, 16.95, 17.96, 19.02, 20.15, 21.35, 22.62, 23.97, 25.39, 26.90, 28.50, and 30.19. The foregoing numbers are in the relation of the frequencies of the equitempered scale each being larger than the one just preceding by the twelfth root of 2.

Fig. 3 shows schematically the entire generator assembly. The synchronous motor 37 drives the line shaft 38 through the belt 39. This line shaft drives the twelve generator groups 40 through the belts 41 each pulley 42 being of such size as to drive its generator group at one of the speeds listed above. In operation the metal parts of all generators are grounded.

Fig. 4 shows a schematic diagram of the manner in which the generators are connected into the circuit so as to allow the musician to control them from the keyboard. 43 is the lowest C key on the keyboard; 44 is the next higher C key and 45 the next higher C above 44. These keys are provided with a multiplicity of contacts 46 arranged as shown so that when the key is depressed the primary inductors of the generators 47 are connected to the polarizing battery 48 through the voltage selecting switches 49 and the variable resistors 50; but when the keys 43 are released the primary inductors of generators 47 are connected to ground through the variable resistors 47 and 51. The contacts on each key of course connect with those generators with frequencies appropriate to the fundamental and harmonics of that particular note in the scale. The symbol which has been chosen to represent these electrostatic generators in the diagram is that for a condenser with a numeral in the center which indicates the number of holes in the row of that particular generator. It will be noted from the drawings that the 1 hole generator is controlled by the fundamental contact on the lowest key, 43. The two hole generator is controlled by the second harmonic contact on key 43 and also by the fundamental contact on key 44. The connections are so arranged that if either key is depressed the primary inductor of the generator is disconnected from the grounding resistor 51 and connected to the 150

appropriate polarizing voltage. Similarly the 4 hole generator is controlled by the fourth harmonic contact of key 43, by the second harmonic contact of key 44, and by the fundamental contact of key 45. Again if any of these keys is depressed the 4 hole generator is disconnected from the grounding resistor 51 and connected to the voltage, determined by the switches 49, of that harmonic which the 4 hole generator furnishes for the key which was depressed. Enough has been said to indicate the manner in which the C keys are connected with the C group of generators. The C sharp keys and the C sharp group of generators form a set of connections separate from the C keys except that the C sharp group derives its polarizing voltage from the same switches 49 and the secondary inductors of the C sharp generator group are also connected to the input grid of the amplifier 17. Similarly for the other notes of the scale. The secondary inductors of all the generators are permanently connected to the input grid of the amplifier 17 and thence through the potentiometer 19 to the loud speaker 18, but alternating voltage is supplied only by those generators whose primary inductors are charged. If the generators are built for 20 harmonics of each note then there will be 20 sets of contacts 46 on each key except those near the top of the scale, and 20 sets of resistors 47 and 51 and condensers 52 for each key except those near the top of the scale. There are, however, only 20 switches 49 for each manual of the organ as one switch regulates the voltage for all the fundamental frequencies, another switch regulates the voltage for all the second harmonic frequencies, etc. By setting the switches 47 the musician has absolute control of the steady state tone quality of the notes produced by the loud speaker 18. The different manuals of the organ use the same set of generators but each manual has a separate set of switches 49 for controlling the relative intensity of the harmonics. Thus while the lowest note played on one manual might consist mainly of fundamental, this same pitch played on another manual might be very rich in harmonics.

The purpose of condensers 52 in conjunction with resistors 50 and 51 is to regulate the attack on the notes as was previously pointed out in the explanation of Fig. 1.

It is obvious from the connections of Fig. 4 that if two keys are simultaneously depressed two voltages may at the same time be applied to one of the primary inductors of a generator 47. In such a case it is desirable that the resultant voltage should be approximately equal to the largest of the two. This result is achieved by placing resistors 53 in series with the voltage supply leads, the resistance in the higher voltage leads being less than the resistance in the lower voltage leads.

In the above description of the method of connecting the generators it has been assumed that there is only one generator of each of the required frequencies and that each generator may serve as a harmonic of several notes. It is obvious, however, that several pairs of inductors might be disposed tangentially along a single row of holes and thus serve as several separate generators of the same frequency without an increase in the number of discs required. In some cases this might be of advantage in simplifying the connections as each harmonic would have its own generator and no generator

would be required to serve more than one purpose.

If it should be found that the relative phase of the various harmonics influences the tone quality, then each pair of inductors on the generators may be arranged to move a short distance tangentially from its normal position and in this way the relative phases of the generated currents can be varied.

The electrostatic generators as described above can be constructed in many forms which will achieve the essential result, namely the periodic variation of the mutual electrostatic capacity between two conductors whose average potential is different. For instance, the disc itself may be insulated from the shaft and connected to the amplifier through a slip ring thereby serving both as moving member and as secondary inductor, the mutual capacity between the disc and the stationary primary inductor varying as the holes in the disc pass. Or with this construction the role of disc and primary inductor might be interchanged. Or the disc can be grounded and the primary inductor grid terminal of the amplifier which in Fig. 1 is attached to the secondary inductor 11 could be connected to the charged primary inductor 10. The passage of the holes in the disc would cause a fluctuation in the potential of the primary inductor 10 which would be amplified by the tube. As regards the means of regulating the attack, in the simple circuit of Fig. 1 the rate of growth and decay of charge on inductor 10 are regulated merely by resistance 21 and condenser 22. These two circuit elements may however be replaced by a more complicated series parallel arrangement of resistances, condensers and inductances, thereby securing a more complicated form of attack and decay, the exact form of circuit chosen depending on the judgment of musical taste on listening to the notes produced. The amplifier may utilize as many stages as necessary and be of sufficient power to supply the necessary volume without harmful distortion. The loud speaker may be any sort of suitable device for converting electrical energy into acoustical energy although it is preferable that it should have a minimum amount of resonance so that the response may be quick and free from frequency distortion. A good cone speaker, horn speaker, or Hewlett tone generator would be suitable. Its construction must be such as to allow it to handle the comparatively large energy.

What I claim is:

1. In combination, means of generating alternating currents of a multiplicity of frequencies, a loud speaker, and means for regulating as a function of the time the amount of current of any frequency supplied by said generating means to said loud speaker.

2. In combination, a multiplicity of alternating current generators, a loud speaker, means for starting and stopping the delivery of alternating current from any aforesaid generator to said loud speaker, and means for regulating the rate of starting of the aforesaid delivery of alternating current.

3. In combination, a multiplicity of alternating current generators, a loud speaker, means for starting and stopping the delivery of alternating current from any aforesaid generator to said loud speaker, means for regulating the rate of starting of the aforesaid delivery of alternating current, and means for regulating the rate of stopping of the aforesaid delivery of alternating current.

4. In combination, means of generating alternating currents of a multiplicity of frequencies, a loud speaker, and means for regulating as a function of the time the amount of current of any frequency supplied from said generating means to said loud speaker. 80
5. In combination, means of generating alternating currents of a multiplicity of frequencies, means for regulating as a function of the time 10 the amount generated of alternating current of each frequency, an amplifier, and a loud speaker. 85
6. In combination, means of generating alternating currents having the frequencies of the notes of the musical scale and their harmonics, 15 means for regulating as a function of the time the amount generated of alternating current of each frequency, an amplifier, and a loud speaker. 90
7. In combination, a multiplicity of alternating current generators, means for amplifying alternating currents, means for starting and stopping the delivery of alternating current from any aforesaid generator to said amplifier, means for regulating the rate of starting and the rate of 20 stopping of the aforesaid delivery of alternating current, and means for producing sounds from the amplified alternating currents. 95
8. In combination, a multiplicity of alternating current generators, generating the frequencies of the notes of the musical scale and their harmonics, means for amplifying the alternating currents generated by said generators, means for starting and stopping the delivery of alternating current from each aforesaid generator to said amplifier, means for regulating the rate of starting and the rate of stopping of the aforesaid delivery of alternating current, and a means for 30 producing sounds from the amplified alternating currents. 100
9. In combination, a multiplicity of alternating current generators, a console, means for amplifying alternating currents, means controllable from said console for regulating as a function of the time the amount of alternating current delivered from any aforesaid generator to said amplifier, and means for producing sounds from the amplified alternating currents. 105
10. In combination, a multiplicity of alternating current generators generating the frequencies of the notes of the musical scale and their harmonics, a console, means for amplifying alternating currents, means controllable from said console for regulating as a function of the time the amount of alternating current delivered from any aforesaid generator to said amplifier, and means for producing sounds from the amplified alternating currents. 110
11. In combination, a multiplicity of electrostatic alternating current generators each of which comprises a moving member, a primary inductor, and a secondary inductor, the mutual electrostatic capacity between said primary and secondary inductors being periodically varied by said moving member; a console having several 60 manuals of keys; separate means for each manual for controlling the charge on the primary inductor of any generator as a function of the time; means for amplifying the alternating currents produced by said generators; and means for producing sounds from the amplified currents. 115
12. In combination, a multiplicity of electrostatic alternating current generators each of which comprises a moving member, a primary inductor, and a secondary inductor, the mutual electrostatic capacity between said primary and 65 secondary inductors being varied periodically by said moving member; means for controlling the charge on the primary inductor of any generator as a function of the time; means for amplifying the alternating currents produced by said generators; and means for producing sounds from the amplified currents. 120
13. In combination, a multiplicity of electrostatic alternating current generators each of which comprises a moving member, a primary inductor, and a secondary inductor, the mutual electrostatic capacity between said primary and secondary inductors being varied periodically by said moving member; a console; means for charging and discharging the primary inductors of said generators; means for controlling the rate of charge and discharge of any of said primary inductors; means for amplifying the alternating currents generated by said generators; means for producing sounds from the amplified currents; and means for controlling the amount of alternating current delivered by said amplifier to said sound producing means. 125
14. In combination, a multiplicity of electrostatic alternating current generators each of which comprises a moving member, a primary inductor, and a secondary inductor, the mutual electrostatic capacity between said primary and secondary inductors being varied periodically by said moving member; a console; means operable from said console for controlling the charge on any of the primary inductors of said generators; means for amplifying the alternating currents generated by said generators; means for producing sounds from the amplified alternating currents; and means for controlling the amount of alternating current delivered by said amplifier to said sound producing means. 130
15. In combination, a multiplicity of electrostatic alternating current generators each of which comprises an insulated primary conducting plate, an insulated secondary conducting plate, and a moving member so shaped and so placed as to periodically vary the mutual electrostatic capacity between said primary and secondary conducting plates; means for controlling the charge on the primary conducting plate of any generator as a function of the time; and means for producing sounds from the voltages induced on the secondary conducting plates. 135
16. In combination, a multiplicity of electrostatic alternating current generators each of which comprises an insulated primary conducting plate, an insulated secondary conducting plate, and means for periodically varying the mutual electrostatic capacity between said primary and secondary conducting plates; means for controlling the charge on the primary conducting plate of any generator as a function of the time; and means for producing sounds from the voltages induced on the secondary conducting plates. 140
17. In combination, a multiplicity of electrostatic alternating current generators each of which comprises an insulated primary conducting plate, an insulated secondary conducting plate, and means for periodically varying the mutual electrostatic capacity between said primary and secondary conducting plates; means for charging the primary conducting plate of any generator; means for utilizing part of the electrical energy induced on the secondary conducting plates. 145
18. In combination, an electrostatic alternating current generator comprising conducting members insulated from each other, means for periodically varying the mutual electrostatic ca- 150

- capacity between said conducting members, means for charging an aforementioned conducting member, and means for utilizing the voltage fluctuations of a conducting member.
- 5 19. In combination, a multiplicity of electrostatic alternating generators comprising conducting members insulated from each other, means for periodically varying the mutual electrostatic capacity between said conducting members, means for controlling the charge on some aforementioned conducting members as a function of the time, an amplifier, and a loud speaker. 80
